UNITED STATES PATENT OFFICE.

HERMAN FROMKESS, OF NEW YORK, N. Y.

PAPER WEIGHT.

1,413,465.

Specification of Letters Patent. Patented Apr. 18, 1922.

Application filed April 6, 1921. Serial No. 458,928.

To all whom it may concern:

Be it known that I, HERMAN FROMKESS, a citizen of the United States, and a resident of the city of New York, borough of 5 the Bronx, in the county of Bronx and State of New York, have invented a new and Improved Paper Weight, of which the following is a full, clear, and exact description.

10 The present invention relates to new and useful improvements in articles of stationery, and it pertains more particularly to paper weights.

It is one of the objects of the invention to 15 provide a paper weight in which it is not necessary to lift the weight to place papers thereunder.

It is a further object of the invention to so construct a paper weight that a maximum 20 holding property with a minimum amount of weight is had.

With the above and other objects in view, reference is had to the accompanying drawings, in which—

25 Figure 1 is a view in elevation, partly in section, of a paper weight constructed in accordance with the present invention, and

Fig. 2 is a top plan view thereof.

Referring more particularly to the drawings, the reference character 5 designates a base and said base is provided with an internally screw-threaded opening 6 centrally disposed therein. Removably carried by the base member 5 is a standard 7, and said 30 standard is provided with a reduced screw-threaded end 8 adapted to be received within the opening 6 and forming the means by which the standard 7 is secured to the base 5. The upper end of the standard 7 is bifurcated as indicated by the reference character 10, and mounted between the bifurcations of the upper end of said standard and pivotally secured therein by means of a rivet 35 or the like 11, is an arm 12. The arm 12

is of greater length than the standard 7 45 in order that its outer end will contact with the support upon which the base 5 is mounted, at a point removed from the base. The lower end of the arm 12 is provided with a weight 13 in the form of a ball or sphere. 50 This weight 13 is formed spherically in order to provide a curved surface 14, the purpose of which will be hereinafter described.

The device operates in the following manner:

With the weighted member 13 in contact with a suitable support, such, for instance, as a desk or table top, the papers 15 which it is desired to retain in position on said support, have one of their edges presented 60 to the lower curved surface face 14 of the weight 13, and upon forcing the papers they will pass beneath the weight 13 as shown in Fig. 1, without manually grasping and lifting the pivoted arm 12. If, however, it is 65 desired to lift the weight 13 by the arm 12, the arm may be grasped and the weight elevated to permit the papers being slipped thereunder.

I claim:

1. A paper weight comprising a base having a substantially centrally disposed opening, a vertically extending standard removably secured in said opening and having its upper extremity bifurcated, and a weighted 75 arm pivotally mounted in the bifurcated arm of said standard.

2. A paper weight comprising a base having a substantially centrally disposed inferiorly screw-threaded opening, a vertically 80 extending standard having a screw-threaded extremity adapted to be received within said screw-threaded opening to removably secure said standard to said base, and a weighted arm pivotally connected to the upper end 85 of said vertically extending standard.

HERMAN FROMKESS.
